(57) CLAIM

The ornamental design for a boot with a leg extension, as shown and described.

DESCRIPTION

FIG. 1 is a front perspective view of a boot with a leg extension, showing the design;

FIG. 2 is a front elevation view thereof;

FIG. 3 is a rear elevation view thereof;

FIG. 4 is a left side elevation view thereof;

FIG. 5 is a left side elevation view thereof with a strap opened;

FIG. 6 is a right side elevation view thereof;

FIG. 7 is a top plan view thereof; and,

FIG. 8 is a bottom plan view thereof.

The portions of the drawings shown in broken lines form no part of the claimed design.
